UNITED STATES PATENT OFFICE

WILLIAM R. HEWITT, OF NEW YORK, N. Y.

RAILWAY TIE

Application filed August 18, 1930. Serial No. 476,032.

This invention relates to railway ties, and especially to a tie in which the major portion is constructed of metal, while the rail supporting portion is constructed of wood or a similar material.

The object of the present invention is to generally improve and simplify the construction and operation of railway ties; to provide a tie which will have the advantages characteristic of a metal tie and at the same time present the desirable characteristics of a wooden tie; to provide a tie in which the parts subjected to deterioration and wear may be readily removed and renewed; to provide a combination metal and wood tie in which the metal portion may be permanently fixed in the road bed, while the wood portion may be removed or renewed without disturbing the metal tie or the road bed; to provide a tie which is vertically adjustable by the introduction of packing or ballast material between the metal and the wood tie so as to permit leveling of the rails; and, further, to provide a tie to which rails may be readily secured regardless of the gauge or distance between the rails.

The invention is shown by way of illustration in the accompanying drawings, in which—

Fig. 1 is a central longitudinal section of one end of the tie and the rail supported thereby,

Fig. 2 is a plan view of Fig. 1,

Fig. 3 is a cross section taken on line III—III of Fig. 1,

Fig. 4 shows a complete tie and the rail supported thereby, said view being partially in section,

Fig. 5 shows a modified form of the metal tie.

Referring to the drawings in detail, and particularly Fig. 4, A indicates the subsoil of a road bed and B ballast material, such as crushed rock or the like, to form a support for a tie C and the rails D carried thereby. The tie as disclosed forms the subject matter of the present application. It consists of three separable sections generally indicated at 2, 3 and 4, the section 2 being formed of metal, while the sections 3 and 4 are formed

of wood or like material. The metal section forms the main portion of the tie and is preferably constructed of channel iron or steel. Cross plates 5, angle-shaped in cross section, are placed between the sides of the channel and they are there secured by welding as indicated at 6, or by means of bolts such as shown at 7. A pocket is in this manner formed at each end of the channel-shaped tie and these form receptacles for the wooden tie sections 3 and 4. A small amount of packing or ballast material 8 such as sand, gravel, crushed rock, or the like, is placed between the lower faces of the wooden tie sections and the bottom of the channel, the amount of material employed being just sufficient to raise the tie sections 3 and 4 and the rails D carried thereby to the proper level to maintain rail standards.

The rails D may be secured to the wooden tie sections 3 and 4 in any suitable manner, but preferably by the method disclosed in my co-pending application entitled "Tie plate", filed March 26, 1930, Serial Number 439,044. Briefly stated, the method employed consists in interposing tie plates such as shown at 9 between the wooden ties and the rails. These plates are secured to the ties by lag screws 10, said lag screws being provided with square heads 11 at their upper ends, whereby they may be grasped and rotated while inserting them in the ties and being also provided with collars 12 under which are placed springs or spring washers 13. This method of securing the tie plates to the wooden tie sections permits a slight vertical movement of the tie plates with relation to the tie sections and, as a consequence, a slight vertical movement of the rails which are secured thereto, the importance of such vertical movement being clearly brought out in my co-pending application. The rails D are secured to the tie plates by means of bolts 14. These bolts extend through the tie plates and also through side or distance plates 15 and are freely turnable in both, the bolts being secured against endwise removal by heads 16 on their lower ends and by eccentrics 17 on their upper ends. These heads are provided with flattened sides 18 so that

they may be grasped by a wrench or like tool, and when rotated by such a tool in one direction, the eccentric heads will engage the flange of the rail and there be secured, and when rotated in the opposite direction they are turned free of the flange and, as such, permit removal of the rail. Plainly speaking, the rails D are rigidly secured to the tie plates, while the tie plates are more or less resiliently secured with relation to the tie sections 3 and 4, as a limited vertical movement is permitted due to the spring washers 13 employed. It will, however, be understood that any other method of securing the rails D with relation to the wooden tie sections may be employed.

In actual practice it will be understood that the main tie sections, to-wit, the channels C, may be more or less permanently installed in the road bed where they are held against slewing or endwise movement by the ballast material. A slight amount of ballast or packing material, such as indicated at 8, is then introduced in the bottoms of the pockets and leveled off and the wooden tie sections are then inserted and the rails applied. If it is desired to raise or lower the rails when leveling, then the endmost angle plates 5 may be removed by releasing the bolts 7 and packing material may thus be introduced or removed without disturbing the wooden tie sections or the main channel section. The removal of these bolts with the accompanying cross plates 5 permits complete removal of the packing 8 and also endwise removal of the wooden tie sections. This permits overhauling of the tie sections or removal and reinsertion of the same without disturbing either the main channel ties or the rails. If new tie sections are inserted and brought in contact with the rails through the tie plates, it is only necessary to introduce the packing material through the end and tamp until the rail is brought up to proper level. When sufficient packing material has been introduced and tamped, the end plates 5 are replaced and again secured by the bolt 7. Obviously, a track supported in the manner described may be maintained at its proper level with a minimum of effort and with a minimum of cost when comparison is made with the ordinary method which requires complete removal of the ties, disturbance of the road bed, ballast, and so on.

A tie constructed in the manner described should have a long life, as the only parts subject to wear and deterioration are the wooden sections and as these are cheap in comparison with ordinary ties due to their short length, they may be renewed or overhauled from time to time. The tie shown has the advantages characteristic of a metal tie and at the same time possesses the desirable characteristics of a wooden tie. Disturbance of the road bed, the ballast, and of the main tie sec-

tions is prevented and the cost of maintenance should, accordingly, be small.

By referring to Figs. 1 and 4, it will be noted that drain openings 20 are formed in the pockets and in the center of the main channel sections. Such drain openings are desirable as collection of rain and moisture is prevented, thereby lengthening the life of the wooden tie sections.

In Fig. 5 a modified form of the metal tie is shown. In this instance the metal tie is channel-shaped in cross section, but in place of being made up of a single beam, it is constructed of two sections of angle iron such as indicated at 30 and 31. These sections are secured with relation to each other by cross plates such as indicated at 5a, which are welded or otherwise secured thereto and they are also provided with removable end plates 5b to permit endwise insertion or removal of the wooden tie sections 3 and 4 and the packing material 8. By referring to the drawings, it will be noted that the base sections of the angles 30 and 31 do not quite contact each other. The longitudinal slot 32 is in this manner formed in the base portion of the tie and this serves the function of a drain to prevent the collection of moisture.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. A railroad tie comprising a metal tie having a pocket formed in each end thereof for the reception of a pair of short wood ties, and a loose packing adapted to be introduced between the bottom of each pocket and the wood ties.
2. A railroad tie comprising a metal tie having a pocket formed in each end thereof for the reception of a pair of short wood ties, a packing of loose material in the pockets, a removable end plate for each pocket to permit endwise insertion or removal of the wood ties and packing material.
3. In a railroad tie, a metal pocket, a loose granular material in said pocket, and a non-metallic member carried by the pocket and resting on the granular material.
4. In a railroad tie, a metal pocket, a granular packing material in said pocket, a non-metallic member carried by the pocket and resting on the granular material, and means for effecting an increase or reduction in the quantity of packing material in the pocket without removing the non-metallic member therefrom.
5. A railroad tie comprising a metal mem-

ber having pockets formed therein, sand in the pockets, and wooden rail supporting members carried by the pockets and resting on the sand.

5 6. The combination with a metal railway tie having non-metallic blocks for the support of rails, of a quantity of loose granular material interposed between the metal tie and the non-metallic blocks.
